UNITED STATES PATENT OFFICE

2,611,532

TURBINE DRIVEN COMPRESSOR

Birger Ljungström, Stockholm, Sweden

Application September 22, 1945, Serial No. 618,042
In Sweden September 23, 1944

1 Claim. (Cl. 230—116)

1

The present invention relates to a power plant comprising a gas turbine and a compressor directly connected thereto and in which the power is delivered from the gas turbine through combustion gases of high velocity and/or high pressure. Said combustion gases may be utilized either for the propelling of aeroplanes, projectiles, ships or carriages according to the reaction principle or for driving another gas turbine in which the dynamically available energy of the combustion gases as delivered from said first-mentioned turbine is utilized for driving a power shaft or shafts.

Said last-mentioned turbine, hereinafter referred to as the power turbine, especially when it is desired to obtain a compact plant, may be arranged as a direct continuation of the driving turbine of the compressor, or it may comprise a separate machine, the gas inlet of which communicates with the combustion gas outlet of the first turbine. In such case, for instance, the power turbine may be situated coaxially outside the first turbine in the outlet of an additional combustion chamber located between the two turbines. In the said last-mentioned case the rotary machines with associated combustion chambers may be assembled so as to form a circulation system in order to permit an efficient utilization of the energy and heat content of the driving fluid. In such a circulation system the coaxial positioning of the turbines with relation to each other may be dispensed with and a heat exchanger may be inserted in the system where required.

The combined compressor and driving turbine therefor comprises three main parts, comprising two rotary engines or machines, namely a gas turbine and a turbine type of compressor, both of multi-stage type, and a shaft system provided therebetween, which comprises a set of tubular shafts concentrically surrounding each other and rotatable independently of each other, and in which each tubular shaft is connected at one end to a blade wheel (or wheels) of the turbine and at the other end to a blade wheel (or wheels) of the compressor.

The above said shaft system permits transmission of power from individual blade wheels of the turbine to individual blade wheels of the compressor. Merely by adjusting the angles of blade it is possible to secure any desired peripheral speed of the individual blade wheels, as for instance, the same speed, irrespective of differences in diameter, and cause them to run in the same direction or in opposite directions.

If, by testing, a preferred type of blade wheel

2

is obtained, then the proportions of this blade wheel may be applied to all sizes of wheel of one and the same engine or machine, provided the dimensions of the various wheels are selected in proper progression and all of them rotate at the same peripheral speed. The centrifugal force, the efficiency, the maximum output of power, and the speed of flow of the driving fluid may in such case be made substantially equal for all blade wheels, irrespective of such changes of pressure and/or volume as may occur during the flow of the driving fluid due to the operating conditions.

In case of a single rotating system the invention allows the connection of any or all of the tubular shafts at one end or both to more than one blade wheel, say two or three, or to different numbers of blade wheels at opposite ends. Such a modification reduces the number of tubular shafts required for a given number of blade wheels, but, on the other hand, reduces the possibility of obtaining a maximum output from each blade ring, and causes a corresponding increase of the weight of the rotary system.

The most efficient way in which to use the invention is to connect the tubular shafts to but a single blade wheel at either end. In this case every second blade wheel of the turbine and the compressor rotates in one direction and the remaining blade wheels in the opposite direction so that adjacent blade wheels of one and the same engine or machine always rotate in opposite directions. Of course, the angles of blade are selected so as to allow the driving fluid to pass from one blade wheel to another without the aid of guide blades inserted therebetween.

The double rotation principle, resulting in a doubling of the relative speed, reduces the number of blade wheels required for a given fall in heat to a fourth. This effect may be increased by using the same peripheral speed of all the blade wheels as above mentioned which effect may be obtained without any additional means.

Under otherwise unchanged conditions, for instance, with respect to the thermodynamic efficiency, it is thus possible in carrying this invention into effect, to reduce in a high degree the weight of the rotary system as compared with a single rotation system having but one shaft, and to correspondingly reduce the dimensions of the plant as a whole.

The reduction of the weight reduces, especially in case of an aeroplane, the power and fuel consumption and increases the radius of action.

Invested in a larger plant the reduction of the weight may be utilized either to obtain a higher speed or a higher efficiency.

In the accompanying drawings,

Fig. 1 illustrates the invention as embodied in a machine for driving an aeroplane according to the reaction principle. Fig. 1 shows a diagrammatic axial section of the machine.

Fig. 2 is a side elevation, partly in axial section, of one end of the shaft system of said machine.

Figs. 2A and 2B are detail views of means for locking and sealing blade wheels on shafts.

Figs. 3-6 are detail sectional views showing the attachment of the blades to the blade wheels.

Fig. 7 is a section of the attachment of a blade on a larger scale.

Fig. 8 shows a form of blade roots.

Fig. 9 is a diagrammatic side view of the power plant as inserted in the wing of an aeroplane.

Fig. 10 is a front view of said wing and plant.

Fig. 11 is a side elevation of a tubular shaft system.

Figs. 12 and 13 are diagrammatic views of power plants, the turbine and compressor of which are provided with cylindrical casings.

Fig. 14 is a diagrammatic part sectional side elevation of an embodiment of the invention including besides the compressor and associated driving turbine a power turbine.

Fig. 15 is a diagrammatic view of the invention as embodied in a circulation system.

In Fig. 1 the power plant is shown as located at the rear end of an aeroplane, the arrangement being such as to allow a ready dismantling of the power plant. The power plant illustrated in this figure includes in addition to the three main parts above stated a combustion chamber located between the turbine and the compressor and another chamber provided in the outlet of the turbine which is adapted for effecting a re-combustion, for instance to allow a forced operation. Since the combustion means do not form part of this invention, they are not shown in the drawing; they may be assumed to be of well-known design.

The power plant shown has no power shaft, the delivery of power being effected exclusively by reaction in the turbine outlet.

The mounting of shafts and turbine discs requires both special bearing arrangements and special means for cooling and axially balancing the bearings and the turbine discs as well as special forms of the turbine and compressor casings and special means for tightly sealing the ends of the blades, as will be hereinbelow set forth.

It is preferred to use an oil mist lubricating system particularly in case of a shaft system mounted in ball bearing. In this connection an auxiliary high pressure fan blower is provided which takes its air from the combustion chamber located immediately behind the compressor through separate pipes the flattened sections of which cross the inlet of the compressor in order to form a cooling device for the air withdrawn which is then passed through an oil mist lubricating device or devices placed in front of the inlet of the fan blower.

The said auxiliary fan blower may be driven by means of toothed gearings from the first blade wheel of the compressor or in any other appropriate way.

To start the plant I use a starting motor, preferably petrol driven, provided with an electric starting mechanism. Inserted between said

starting motor and the fan blower is a pawl and ratchet gear.

The first and the last blade wheels of the compressor and the turbine together with the respective tubular shaft are thus started by the action of the starting motor via the fan blower and the associated toothed gearing, thereby forcing the air or driving fluid of the plant in axial direction through the compressor, the combustion chamber and the turbine. The combustion process in the combustion chamber being simultaneously started, the plant as a whole is thus started. The starting motor and its pawl and ratchet gear may then be stopped.

According to an embodiment of the invention the power plant comprises a number, say four, similar units, placed in the wings of an aeroplane. This method of mounting the plant has for its object to reduce the air resistance. As seen from the illustration of this embodiment, the axial distance between the compressor and the turbine will be comparatively long, causing a corresponding lengthening of the intermediate tubular shaft system.

Since the high speeds occurring in a plant of this character due to its comparatively small diameter would cause the long tubular shafts to exceed their critical speed, if they were made altogether cylindrical, the said shafts are formed with conically tapering ends, the thickness of wall required at the ends being correspondingly reduced towards the middle of the shafts, resulting in an increased critical speed.

A tubular shaft system of this construction prevents the assembling of the tubular shafts by pushing them into each other in finished state. To overcome this difficulty the various tubular shafts may either be made in two parts connected together by welding or otherwise in assembling the system, or the shafts may first be cylindrical to allow their insertion into each other and then conformed at their ends to the cross section desired according as the mounting is proceeding shaft by shaft from inside outwards. The various steps involved in this method of mounting do not cause any essential troubles, particularly as differences in respect of the radial plays of the shafts are of no importance as far as the operation of the shaft system is concerned.

The fastening of the blade wheels to the ends of the tubular shafts may be facilitated by thickening the walls of the shaft ends by an amount corresponding to the plays existing between entirely cylindrical shafts. As an alternative, the shaft ends of the assembled shaft system may be provided with separate stiffening pieces at their ends in the form of bushings attached by pressing or welding which may either be provided with means for receiving the blade wheels or afterwards worked for the same purpose.

The labyrinth packings hereinafter referred to in the specification and the claim may be of well known character and are, therefore, not illustrated in detail but only indicated in conventional manner. The invention has nothing to do with the construction of such packings but includes their use in novel and characteristic combinations with a view to lubricating the tubular shaft system, cooling the blade wheel systems and obtaining a good sealing between the blade wheel systems and the casings of the compressor and the turbine.

To this end a feature of the invention relates to a novel construction of the blade wheels

proper in which each blade wheel is composed of two axially abutting discs between which there is a space surrounded by walls the thickness of which decreases outwards like the thickness of an undivided blade wheel of conventional design. Said novel structure of the blade wheels has for its purpose to permit a good cooling of the blade wheels so that their surfaces facing each other may be situated at a short distance apart and provided with labyrinth packings for cooling purposes.

The blade wheel structure above described permits shaping and mounting the labyrinth packings with a view to obtaining both a balancing of the axial thrusts appearing between the blade wheels and a reduction of the quantity of lubricating oil and cooling fluid passing between the wheels of each pair of wheels. Thus it is possible to control the distribution of the cooling fluid to the various pairs of wheels and to reduce the total quantity thereof required. The dimensions and power of the fan blower and the losses inherent thereto may be reduced accordingly.

Though, hereinbefore, the blade wheels have been assumed as rigidly connected to the tubular shafts against axial movements, it is evident, however, that they may be connected thereto by axially adjustable means, provided the axial position of the blade wheels with relation to each other is stabilized and maintained by the use of appropriate labyrinth packings subjected to axial pressure transmitted by the cooling fluid.

The flow of the cooling fluid from between the outer edges of the blade wheels to the driving fluid passing between the blade rings serves an additional purpose, inasmuch as the cooling fluid prevents leakage of the driving fluid into between the blade wheels, that is, past the inner ends of the blades.

The leakage past the outer ends of the blades, that is, past the outer periphery of the blade wheels, involves another problem, namely sealing each blade ring with respect to the inside of the turbine and compressor casings. This problem is intimately related to the introduction of the tubular shaft system and the use of double rotation.

The turbine and compressor casings support no guide blades or the like between the blade wheels. Instead thereof special packing means of heat elastic kind are provided which may suit, independently of the casings, such changes of the radius of the rotary system, including the expansion and contraction of the turbine blades, as are due to sudden changes of load or to a quick starting. By this means a lagging of the expansion or contraction of the turbine and compressor casings resulting from said changes of temperature do not require any increased plays. This means a special advantage, since the packings of all blade wheels are positioned at the greatest radius of the blade wheels where there are very great falls in pressure between each two adjacent blade wheels due to the double rotation.

The packing means provided on the inside of the turbine and compressor casings comprise well known expansion elements.

Instead of mounting the shaft system on a tubular stationary shaft, as above mentioned, I may use the innermost, or central, rotary tubular shaft to support the surrounding shafts. To this end said innermost shaft should be mounted in bearings at both ends. In this case the power to

drive the fan blower may be derived from one free end of said shaft.

As shown in Fig. 1 the power plant is mounted in the rear end of the aeroplane body by means of a flange 1. The main parts of the plant comprise the inlet 2, the compressor 3 with associated casing 3b, the turbine 5 with associated casing 5b, a cylindrical wall 4b connecting the casings 3b and 5b which forms a combustion chamber 4, and an outlet 6. Said members form together a unitary structure surrounding the tubular shaft system 7 supported by a central stationary shaft 12 which is guided at both ends by bushings 8 and 9 carried by or formed integrally with stationary guide blade wheels 10 and 11 provided at opposite ends of the compressor and turbine bladings, respectively. The said central shaft 12 supports ball bearings 13 and 14 serving to guide the first pair of blade wheels 15, 16 and the associated tubular shaft 17 carrying said wheels.

The tubular shaft system shown in Fig. 1 comprises a set of rotary shafts 18-24, which may rotate at individual peripheral speeds with adjacent shafts rotating in opposite directions. The blade wheels of the turbine connected to the shaft system which are numbered 16a to 22a, and those of the compressor which are numbered 15b to 21b, are all mounted on ball bearings to permit independent rotation of each individual shaft. In the drawing the first and last ball bearings belonging to the compressor are shown at 13 and 26, respectively, and the first and last ball bearings of the compressor are shown at 25 and 15, respectively. The innermost ball bearings of the compressor and the turbine, namely 26 and 25, are supported by guide blade rings 28 and 27 and the insulating bushing 29 inserted therebetween, in order that also the outermost tubular shaft 24 may be positively guided by the casing of the plant.

The tubular shaft system together with the blade wheels connected thereto is positively guided at its outer ends by the ball bearings 13 and 14 and in the middle of the system by the ball bearings 25 and 26 as already stated, whereas the ball bearings situated between 14 and 25 and between 13 and 26 are centered within the turbine and compressor casings respectively by the action of said first-mentioned bearings.

The cooling system of the power plant comprises means for withdrawing air from the combustion chamber 4 through pipes 30 symmetrically arranged around the plant, said pipes 30 passing through the air inlet 2 of the power plant in the form of flattened pipes 31 connected at both ends to concentric collecting pipes 32 and 33 for constituting the cooling system of the plant. From said collecting pipe 33 the cooled air is passed through one or more radially positioned pipes 34 to one or more lubricating apparatus 35 operating according to the mist system, and from there the air is passed to the inlet of the auxiliary high pressure fan blower 36. The fan blower forces the oil mist at an increased superpressure through the tubular shaft 12 into the centre of the shaft system along the entire length thereof.

The said high pressure fan blower is connected by means of toothed gears 37 and 38 to a blade wheel 15 and is further connected by means of the pawl and ratchet gear 39 to the starting motor 40 which may be provided with an electric automatic starting device, not shown.

In Fig. 1 the reference numeral 41 indicates the entrance of the cooling and lubricating oil mist into the spaces between the various tubular shafts, in which spaces said oil mist may be passed to the various rotary elements of the plant.

In Fig. 2 is shown an axial section of one end of the shaft system including the stationary central pipe 12 and the rotary shafts 18 and 24. In this drawing both the guiding ball bearings 14 and 25 and the other ball bearings which are situated between the turbine disc to centre the turbine discs and the rotary shafts are shown. The turbine discs 18a and 22a are fastened to the respective tubular shafts by being screwed on the threaded ends thereof. Said threaded ends are of a greater thickness than the remainder of the shafts. The fastening of the turbine disc 17a is also effected by screwing, but in this case the turbine disc is not in direct contact with the shaft end, inasmuch as a set of wedges 42 of thin sheet metal is inserted between the shaft and the turbine disc, said wedges being flexible, so that they may act as seals for the lock nut 43. The blade wheel 16a illustrates another modification in which the tubular shaft 18 is provided with a bushing 44 pushed thereon which is connected to the shaft by welding, as indicated at 45. The connection between the blade wheel and said bushing is effected by means of keys 46 and lock nut 47 with associated washer 48.

Figs. 2A and 2B show details of said two last-mentioned fastenings.

The above said different fastening methods may be applied to all blade wheels. The second method requires mounting of the hubs of the blade wheels subsequent to the introduction of the tubular shafts into each other, which prevents the shafts from being dismantled in the same way.

As indicated at 49 the cooling fluid may be introduced between all tubular shafts through a radial set of apertures, while as shown at 50 the discharge of the lubricating fluid from between the tubular shafts may take place at axially displaced points to the spaces between the blade wheels inside the bearings thereof. As already indicated the cooling and lubricating fluid is then passed through the ball bearings radially outwards between the blade wheels, as will be clear from an inspection of Fig. 3.

Said Fig. 3 shows an axial section of two adjacent blade wheel discs 53 and 53b with associated shaft end ball bearings. Radially outside the ball bearings are labyrinth packings 51 and 52 situated at radially spaced places adjacent the ball bearings and the outer periphery of the discs, respectively. The cooling and lubricating fluid will thus flow to the blade system through the labyrinth packings and escape together with the driving fluid. It is to be noted, that labyrinth packings may also be provided along the remaining portion of the opposite surfaces of the blade wheels.

According to Fig. 3 the blade wheels are each composed of two axially displaced discs 53 and 53b welded together at their inner and outer peripheries so that they will constitute a hollow body the space of which is indicated by the reference numeral 54. The purpose of this construction has already been pointed out hereinbefore. The blades shown in Fig. 3 may be fastened to their respective blade wheels by welding, preferably resistance welding.

Figs. 4, 5 and 6 illustrate another method of fastening the blades between the two discs of each blade wheel. According to this method the blades are fastened to or formed integrally with blade roots 55 of special shape, as shown in Figs. 6, 7 and 8. Fig. 7 illustrates the fastening method on a larger scale. It is evident from the drawing that the caulking wire 56 causes a firm engagement at 57 as and for transmitting the centrifugal stresses and interconnecting the two discs 53 and 53b.

Figs. 4 and 5 show a form of blade roots 55 having a thin radial web 58 projecting from its inner surface, said web due to its small thickness having a great resistance to heat conduction thereby reducing the amount of heat transmitted from the blades and the blade roots to the blade wheel discs.

Fig. 3 illustrates a form of tightening device provided on the inside of the turbine and compressor casings, which are adapted to prevent leakage of driving fluid beyond the tops of the blades or beyond the outer edges of the blade wheels. In its most simple form said device consists of axial projections 59 at the inside of the conical casing 5b. As shown at 60 said axial projections may be replaced by thin sheet metal rings of angular cross section, which are inserted in grooves formed in the casing and sealed into engagement therewith by means of caulking wires 61.

Fig. 4 illustrates a more structural form of device for the same purpose. Here, said device comprises a separate ring 62 connected by means of an expansion ring 63 to a seating ring 64 seated in a groove of the casing 5b and sealed in this engagement by means of a caulking wire 65. This device allows an independent contraction of the ring 62 with relation to the casing 5b due to changes of temperature and operation. A channel-shaped ring 66 situated inside ring 62 which is provided at the top of the blade is formed with two tightening ridges which may be worn in operation with but little heat generation until the play required by the operation is obtained.

In Fig. 9 is shown a power plant according to the invention as located in the wing of an aeroplane. In this case the compressor 3 and the turbine 5 are connected for practical reasons to each other by means of a very long tubular shaft system 67, the construction of which is shown in Fig. 11. Said shaft system may be assumed to be constructed according to the principles above set forth.

In Fig. 10 the wing with the power plant there-in is shown in front elevation, the air inlet opening being specially indicated and the entire structure being shaped with a view to obtaining the smallest air resistance possible.

Figs. 12 and 13 are diagrammatic views of power plants having cylindrical instead of conical compressor K and gas turbine T, the diameters of both being either equal, as shown in Fig. 12, or different, as shown in Fig. 13, with the diameter of the compressor considerably greater than that of the turbine.

In aeroplanes for very high speeds the air resistance will be considerable even as far as the individual reaction plants are concerned. The air resistance of such a plant is approximately proportional to the largest section area of the plant. Said area cannot be reduced beyond the dimensions determined by the diameter of the compressor and the inlet area thereof as calculat-

ed for a given quantity of air and the most appropriate angles of blade as seen from the efficiency point of view, which all results in a certain axial inlet speed.

The outer air resistance of the plant will under these conditions become almost inversely proportional to the axial inlet speed.

Said inlet speed may be the double one of a single rotation compressor having the same angles of blade due to the double rotation, which means a corresponding reduction of the diameter of the compressor as well as of the air resistance. It is to be noted that a further reduction of the diameter with larger angles of blade at the inlet is economically grounded, even at the cost of the efficiency of the compressor, if this measurement results in a corresponding reduction of the diameter of the plant, that is to say, a reduction of air resistance and weight and thus also of the weight of the aeroplane and the total air resistance thereof. This fact seems not to have been duly considered in case of prior proposals.

As a result, I obtain a power plant having a comparatively very small compressor diameter, while the turbine diameter may be still more reduced without interfering with a high efficiency. Thus, the plant as a whole will obtain the smallest outer dimensions possible or the smallest outer air resistance.

The diameters of the compressor and the turbine will, however, even at the highest efficiency, be nearly equal. It is to be noted that the figures of the drawing above discussed show examples of the invention only but do not mean limitations of the scope of the invention.

Hereinbefore, the invention is described as applied to a power plant for the propelling of aeroplanes according to the reaction principle. It is to be noted, however, that the invention may be applied in other connections, where combustion gases, produced under a high pressure, are utilized, as for instance, for the propelling of projectiles, ships, carriages and so on as well as for stationary power generating purposes.

Examples of such modified plants are illustrated in Figs. 14 and 15.

In Fig. 14 the numeral 101 designates a stationary guide blade ring provided at the inlet of the turbine type of compressor, while 102 designates the blade wheels of said compressor. The guide blade ring 101 is connected at its outer periphery to the compressor casing 103 and at its inner periphery to a bearing 104 supporting the shaft 105 of the power turbine to be hereinbelow described. The blade wheels 102 of the compressor are of diameters gradually decreasing from the inlet towards the outlet of the compressor. Each blade wheel is supported by a tubular shaft 106 which carries at its other end a corresponding blade wheel 107 of a gas turbine. In the drawing the tubular shafts 106 are not shown to their entire extent in order not to render the illustration obscure but only their ends are shown. The individual tubular shafts 106 may rotate independently of each other. To this end ball bearings 108 are inserted between the blade wheels 102 of the compressor, and similar ball bearings 109 are inserted between the blade wheels 107 of the turbine. Between the outlet end of the compressor and the inlet end of the turbine is a stationary partition 110, which projects outwards into a combustion chamber 111 surrounding the compressor and turbine casings. Said partition forms a baffle which acts to guide

the compressed fluid that passes from the compressor out into the combustion chamber as well as the gases which after mixing with fuel injected by means of the nozzle 12 and ignition enter the turbine.

Both the turbine pipe of compressor 102 and the gas turbine 107 are double rotating but may without departing from the principle of the invention be replaced by single rotating machines. As an immediate continuation of the gas turbine 107 that drives the compressor is provided a single rotation power turbine of conventional type comprising a set of stationary guide blade rings 113 and a corresponding set of rotary blade wheels 114. The latter are connected to the said first-mentioned shaft 105 which is mounted at its one end in the bearing 104 above referred to and at its other end in a bearing 115 positioned outside the turbine 114, preferably in combination with the outlet thereof. Outside the bearing 115 the shaft 105 carries a flange 116 for its coupling to a driven shaft. The exhaust gases expelled from the turbine 114 are discharged through the outlet 117 to be then passed, for instance, to a plant for recovering their heat content.

In the plant diagrammatically illustrated in Fig. 15 the gas turbine adapted to deliver power through its shaft is mounted separately, at a distance from the compressor and its driving turbine. Provided between the outlet of the compressor 120 and the inlet of the driving turbine 121 is a combustion chamber 122 and in front of the power turbine 123 is another combustion chamber 124. The system also includes a heat exchanger 125. In order to render the insertion of the heat exchangers into the system more easily the compressor and its driving turbine are so related to each other that their outlets are facing each other.

The fluid to be compressed is drawn into the compressor as indicated by the arrows *a* and passes from the compressor through the heat exchanger 125 where its already very high temperature (say 300° C.), due to compression, is further increased (say to 450° C.) by the admission of heat from the gases discharged from the power turbine 123. The fluid then enters at this high temperature the combustion chamber 122 where it is mixed with fuel and the mixture resulting is ignited. The combustion gases produced which obtain a still increased temperature (say 900° C.) enter the driving turbine 121 of the compressor where they deliver part of their energy content under reduction of their pressure and temperature (say to 600° C.). The gas expelled from the turbine 121 is not passed directly to the power turbine 123 but is first led through the combustion chamber 124 where fuel is added and combustion again established. This produces another increase of temperature up to the maximum value (say 900° C.), and the heat gases produced enter the power turbine 123 where their energy is transformed into work delivered through the shaft 126. The gases discharged from the turbine 123 maintain still a comparatively high temperature (say 500° C.) and are therefore passed through the heat exchanger 125 where part of their heat content is recovered. The remainder of the heat content corresponding, for instance, to a temperature of 350° C., may be utilized for water heating and/or similar purposes.

The temperatures above stated within parentheses are, of course, quite approximative and

11

mentioned only as an illustration of the heat situation within the plant.

Even in case of the structures illustrated in Figs. 14 and 15 modifications may be made by the use of compressors and driving turbines therefor of cylindrical shape instead of the conical compressors and driving turbines shown. These modifications may also be considered to be illustrated by Figs. 12 and 13, where K indicates the turbine type of compressor and T the driving turbine therefor. Said engines may either be of the same diameter, as shown in Fig. 12, or of different diameters, as shown in Fig. 13.

What I claim is:

In a machine of the character described, the combination of a spool-shaped casing having an air inlet at its one end and an exhaust gas outlet at its other end, a stationary shaft centrally arranged in said casing; a set of tubular rotatable shafts concentrically surrounding said central shaft with the ends of each inner tubular shaft projecting beyond the ends of the adjacent surrounding shaft, a compressor blade wheel supported by one projecting end of each tubular shaft, a turbine blade wheel supported by the other projecting end of each tubular shaft, a bushing stationarily arranged in the casing around the outermost tubular shaft, adjacent blade wheels being axially spaced from each other and having radially spaced concentric flanges on their sides facing each other so as to enclose an annular space between each two adjacent

12

blade wheels, a ball bearing inserted in each such annular space and other ball bearings inserted in similar annular spaces formed between the blade wheels of the innermost tubular shaft and the stationary central shaft as well as between the outermost tubular shaft and said stationary bushing.

BIRGER LJUNGSTRÖM.
